UNITED STATES PATENT OFFICE.

ARTHUR L. REMINGTON, OF WORCESTER, MASSACHUSETTS, ASSIGNOR TO WARP COMPRESSING MACHINE COMPANY, OF WORCESTER, MASSACHUSETTS, A CORPORATION OF MASSACHUSETTS.

MACHINE FOR FORMING YARN PACKAGES.

Application filed February 23, 1922. Serial No. 538,643.

To all whom it may concern:

Be it known that I, ARTHUR L. REMINGTON, a citizen of the United States, residing at Worcester, in the county of Worcester 5 and Commonwealth of Massachusetts, have invented a new and useful Improvement in a Machine for Forming Yarn Packages, of which the following, together with the accompanying drawings, is a specification.

10 My invention relates to machines for winding yarns, and has for its object to provide an improved mechanism that is adapted to form yarn into independent packages of such size that the yarn may later be conveniently wound on bobbins or filling carriers, or the packages may be used in various color combinations to constitute a warp in weaving.

20 A further object of my invention is to adapt my improved mechanism for use in connection with an inspection frame on which the yarn may be conveniently examined in order to permit the removal of all imperfections therefrom before forming it 25 into packages. Further advantageous features of my invention will hereinafter more fully appear, reference being had to the accompanying drawings in which,

Fig. 1 is a view in side elevation of a machine embodying my invention.

30 Fig. 2 is a plan view of the parts shown in Fig. 1.

Fig. 3 is a view in front elevation showing the parts of my improved mechanism on an 35 enlarged scale.

Fig. 4 is a view in end elevation of the parts shown in Fig. 3.

Fig. 5 is a vertical sectional view along the line 5—5, Fig. 3.

40 Fig. 6 is a fragmentary sectional view along the line 6—6, Fig. 5.

Like reference characters refer to like parts in the different figures.

45 Referring to Figs. 1 and 2, my invention is shown, for the purpose of illustration, in connection with an inspection frame 1 which provides inclined side members 2, between which are rotatably mounted a number of spaced shafts 3. Each shaft 3 is provided at one end with a bevel gear 4 in mesh with a pinion 5 mounted on a shaft 6, extending the length of the frame 1, parallel to one of the side members 2. The shaft 6 is adapted to be driven from a suitable source of

power, not shown. A cylinder 7 having a 55 frictional surface is mounted on each of the shafts 3 and one of my improved winding mechanisms is adapted to cooperate with each of the cylinders 7, as will now be described.

60 As best shown in Fig. 3, a pair of vertical standards 8 are secured to the side members 2 at opposite points on the frame 1, adjacent to each of the shafts 3, and each standard 8 is provided with a longitudinal 65 slot 9 extending the length thereof. A shaft 10 extends between the standards 8 with reduced end portions 10^a loosely received in the slots 9, and the shaft 10 is provided with a plurality of spaced yarn carriers 11 which, 70 when empty, are adapted to rest on the periphery of the cylinder 7. A pressure roll 12 is supported at its ends in slide blocks 13, each of which is provided with a tongue 13^a received in a slot 9 of one of the standards 8, as best shown in Fig. 6. A traversing bar 14 is slidably supported near its ends 75 on the blocks 13 by means of bolts 15 received in slots 16. The traversing bar 14 is provided along its lower edge with a plurality of spaced notches 17, the distance between adjacent notches being substantially 80 the same as the distance between the center lines of adjacent yarn carriers 11. The bar 14 is adapted to receive a longitudinal reciprocatory movement, as will now be described.

85 As best shown in Fig. 3, the right hand end of the shaft 3, supporting the cylinder 7, is provided with a gear 18 which is in mesh with a pinion 19 mounted on a countershaft 90 20, extending substantially parallel to the shaft 3. A cam 21 provided with a groove 22 is carried on the shaft 20, and a lever 23 is provided at its end with a roller 24 received in the groove 22. The lever 23 is 95 pivotally supported at a point intermediate its ends on a stud 25 which is received in a slot 23^a, for the purpose of adjustment, and the upper end of the lever 23 is pivotally connected to a cross head 26, by means of a 100 pin 27. The cross head 26 is slidably supported between guides 28 secured to one of the standards 8. The cross head 26 has secured thereto a downwardly extending arm 29, the lower end of which is connected to the traversing bar 14 by means of a link 30. The link 30 is pivotally connected to a block 31 slidably in a slot 32 in arm 29. Rota-

tion of the shaft 3 will cause a vibratory movement of the lever 23 by reason of its connection to the cam 21, and this movement of the lever 23 will in turn be translated 5 into reciprocatory movement of the traversing bar 14, by reason of its rigid connection with the cross head 26.

While only one complete traversing mechanism is shown mounted on the frame 1, in 10 Fig. 1, my invention contemplates the provision of a traversing mechanism operating in connection with each of the cylinders 7. When it is desired to operate the machine the several strands of yarn 33 are taken 15 from a suitable creel, not shown, are passed under roll 34, and are passed over rolls 35 and 36 above the frame. The yarn is then passed downwardly around a roll 37, from which it passes upwardly to a number of 20 spaced rolls 38 rotatably supported one above the other. The separate sets of threads passing over each roll 38 are then led to the traversing mechanisms, described above, each separate thread passing through a 25 feeler 39, pivotally mounted on a shaft 40, extending between the standards 8 above the traversing members 14. When a thread is passing through a feeler 39 it is held in a slightly elevated position, as shown in Fig. 30 5, but should the thread break, the other end of the feeler 39 will be allowed to fall, thereby completing the electric circuit of a signal bell through a contact 41, which circuit is normally open when the feeler is 35 depressed by the passage of thread therethrough. The exact form of the feelers 39 form no part of the present invention and obviously other types of feelers or detectors may be employed.

40 Each thread extends from a feeler 39 into one of the notches 17 on the traversing bar 14 from whence it passes to a yarn carrier 11. Each thread is held in close contact with its yarn carrier by the roll 12 which 45 is adapted to exert considerable pressure on the threads, by reason of the fact that the weight of the traversing bar is entirely supported by the roll 12. The several package carriers 11 are in turn held in close engagement with the cylinder 7.

When the machine is operating, rotation 50 of the cylinders 7 will cause the yarn carriers 11 to rotate therewith, which in turn will cause the threads to be wound on the carriers 11. At the same time, rotation of the shafts 3 will also cause a reciprocatory movement of the traversing bars 14, so that the threads passing through the notches 17 will be laid on the carriers 11 with a traversing movement, thereby building up yarn packages on the carriers that are nearly equal to the width of the carriers. As thread is moved back and forth on a carrier, the pressure exerted by the roll 12 will compress the yarn 65 on the carriers 11 and will serve to maintain

the yarn in the position in which it is laid by the movement of the traversing bar 14. As the yarn packages increase in diameter, the roll 12 is free to move upwardly between the standard 8, carrying the traversing bar 14 therewith, this upward movement of the bar 14 being permitted by reason of its sliding connection with the arm 29 through the link 30 and block 31. The traversing movement of bar 14 may be adjusted by shifting 70 an arm 25^a which carries the stud 25, thereby varying the length of the arm through which the lever 23 acts on the cross head 26.

From the foregoing, it is apparent that I have provided a yarn winding machine that 80 is particularly adapted to form separate yarn packages which may be readily removed from the shaft 10 and placed in a filling winder for transferring the yarn to bobbins or filling carriers, or may be used in 85 various color combinations for a warp. Obviously, the diameter and width of the packages can be controlled as desired, in order to obtain the proper amount of yarn on each carrier 11.

90 My improved compressing mechanism is particularly adapted for use in connection with an inspection frame, of the type shown in Fig. 1, in which the threads are open for thorough examination as they pass over the frame from the creel, thereby affording ample opportunity to remove all imperfections, such as slubs, bad pieces, hard and slack twists, and other defects which are liable to occur in the yarn.

95 While I have shown my invention in connection with a particular type of inspection frame, it is not so limited, but is capable of being applied to other types of frames without departing from my invention, which is only subject to such limitations as may come within the scope of the appended claims.

I claim,

100 1. In a machine of the class described, the combination with a rotating shaft having a plurality of yarn carriers mounted thereon, of a member adapted to lead yarn to each of said carriers, and means for imparting a traversing movement to said member to form a separate yarn package on each carrier, the said member being attached to slides cooperating with guides, and adapted to be moved directly away from the center of said yarn carriers by the 110 building of yarn on said carriers.

115 2. In a machine of the class described, the combination of a plurality of yarn carriers mounted on a rotatable shaft for winding; a traversing member and a pressure roll over said yarn carriers, said traversing member and pressure roll being both attached to slides for movement in vertical guides, so as to carry said pressure roll and traversing member directly away from the 120 center of said yarn carrier as the yarn winds 125 130

on the latter, and to maintain a uniform relationship of the approaching yarn to the partly wound carrier.

3. In a machine of the class described, 5 the combination with a rotating shaft having a plurality of yarn carriers mounted thereon, of a traversing member adapted to lead yarn to said carriers for forming separate yarn packages thereon, and a roll for 10 exerting pressure on the yarn during the formation of the packages, the said traversing member being attached to slides co-operating with guides and being capable of 15 vertical movement with said roll to adjust itself to the size of the yarn packages.

4. In a machine of the class described, 20 the combination with a pair of frame members, a cylinder rotatably mounted between said members, and a shaft having a plurality of yarn carriers mounted thereon and 25 resting on the surface of said cylinder, of a traversing member adapted to lead yarn to said carriers for forming separate yarn packages thereon, and a pressure roll resting 25 on said carriers for supporting said traversing member, said roll and said traversing member being both attached to slides mov-

able in guides, so that they may adapt themselves to the growing yarn carriers.

5. In a machine of the class described, 30 the combination with a pair of frame members, a cylinder rotatably mounted between said members and a shaft having a plurality of yarn carriers mounted thereon and resting on the surface of said cylinder, of 35 a pressure roll resting on said carriers, and a traversing member slidably supported by said roll for leading yarn to each of said carriers.

6. In a machine of the class described, 40 the combination with a pair of frame members, a cylinder rotatably mounted between said members and a shaft having a plurality of yarn carriers mounted thereon and resting on the surface of said cylinder, of 45 a pressure roll resting on said carriers, a traversing member slidably supported by said roll for leading yarn to each of said carriers, and means for imparting a reciprocatory movement to said traversing member 50 for forming a separate yarn package on each of said carriers.

Dated this 15th day of February, 1922.

ARTHUR L. REMINGTON.
